UNITED STATES PATENT OFFICE.

ANDREW J. HOPPER AND HENRY F. PRINDLE, OF OAKLAND, CALIFORNIA.

FUME-CONDENSER.

1,007,356.

Specification of Letters Patent.

Patented Oct. 31, 1911.

Application filed July 5, 1910. Serial No. 570,454.

To all whom it may concern:

Be it known that we, ANDREW J. HOPPER and HENRY F. PRINDLE, citizens of the United States, residing at Oakland, in the county of Alameda and State of California, have invented new and useful Improvements in Fume-Condensers, of which the following is a specification.

This invention relates to condensers, and 10 more particularly to fume condensers.

The object of our invention is to provide a novel, and effective apparatus for eliminating, extracting and abating poisonous fumes of sulfurous dioxid, and condensing 15 or suppressing the deleterious gases arising from smelters, or roast furnaces, acid works, factories and garbage plants.

It is also an object of our invention to 20 provide means in combination which are adapted to receive, cool and condense the poisonous fumes and to abstract therefrom all the metalliferous solids or values resulting from the condensation.

The invention consists of the parts and 25 the construction and combination of parts as hereinafter more fully described and claimed, having reference to the accompanying drawings, in which—

Figure 1 is a side view of the device in 30 partial section. Fig. 2 is an end view of the fume condenser in section.

The illustration represents one form of our apparatus which has been embodied in practice; and comprises a suitable frame A, 35 the lower portion of which forms a fluid holding tank 2, and the upper portion of the tank being entirely closed by a housing B of suitable shape and material to properly house a horizontally mounted partially submerged hollow conical spiral drum or fume gatherer 3, which latter is supported upon a horizontal shaft 4, journaled at 5 upon the frame A. The receiving end of the housing B is provided at one end with an upward projecting section 6 to which may be connected the discharge stack of the furnace or garbage plant, in conjunction with which this apparatus is to be used.

The principal mechanical feature consists 50 of the drum 3, carrying on the inside a spiral or worm construction or flue in the shape of a large conch shell tapered from one end to the other, and having a large mouth and capacity, revolving in the tank 55 or receptacle 2, which latter is filled with chemical or bath, preferably of calcium hy-

drate. The fumes are drawn in by vacuum into the housing B from the stack at every revolution of the receiver of conch shell which takes in a large mouthful of fumes; 60 the mouth 8 as the drum turns being submerged in the bath, and allowing or forcing the liquid to flow through the spiral flue and forcing ahead of it like a water piston, the trapped gases and fumes. The gases 65 are completely washed of the deleterious matters and are delivered to the condenser which has a compartment for eliminating the arsenical compounds and base metals as later described.

A collecting and discharging screw 28 is 70 disposed and turnable in the bottom of the tank, so as to facilitate the removal of the precipitates at a trap 29.

During the rotation of the drum 3 the 75 mouth and chamber with which it is connected become charged when at its upper position with a mass of fumes, and as the mouth 8 revolves into the water at its level 9 the fumes are thereby prevented from 80 escaping, and gradually compressed in a chamber where it is sealed by the upper level of the water.

The contracted discharge end 10 of the fume receiver 3 bears in and communicates 85 with a fixed elbow 11, which discharges downwardly at 12, and below the level of the solution in the tank 2; thus it will be seen that if a large volume of fumes or other fluid be caught by the revolving drum 3 and 90 gradually carried below the water level 9, it is gradually compressed and cooled by reason of its engagement with the liquid in the tank, and eventually escapes through the downwardly opening elbow 12 into that end 95 of the tank.

Preferably a partition 14 divides the main body of the tank from that portion in which the elbow 12 is mounted, so that the rising bubbles of uncondensed gas and fumes will 100 be directed up to the outlet 15. The force of the compressed air discharging from the elbow into the condensing liquid in the tank causes a constant ebullition of the liquid, and the uncondensed portion of the fumes 105 arises, as indicated by the arrow a, and pass upwardly through a flue 15 by which they are directed downwardly through a washing chamber 16.

The fume or vapor inlet 6 of the tank is 110 suitably divided off from the vapor outlet 15, so that the fumes must travel through the

conically arranged spiral flue in the drum; the drum gathering a mouthful of fumes at each revolution, as the open mouth 8 comes across the inlet 6 filling all that portion of the spiral momentarily above the liquid level in the tank, and open to the receiving end of the tank. In this chamber and at its upper portion is mounted a suitable spray nozzle 22 whereby an appropriate fluid solution is discharged in the direction of the incoming uncondensed fumes from the flue 15, so that the fumes are thoroughly cooled and further condensed by the spray and directed against oppositely inclined staggered baffles 17, mounted in a chamber 16, thus continuously changing the direction of the flow of the fumes, and the solution as they descend, eventually depositing the solids and liquids in a receptacle 18, adapted to catch them. An overflow opening 19 allows the surplus liquids to run out of the receptacle 18 and down into the tank 20 from which the water may be continuously drawn, and used over and over again by a suitable pump as 21, which furnishes the pressure with which the fluid is forced through the nozzle 22. Such uncondensed fumes as now pass the baffle plates 17 are drawn upwardly through a series of trays 23, mounted in a vertical chamber 24, by a suction fan 26. Each tray 23 is charged with a suitable granular material, such as charcoal or other substance, so that the fumes are scrubbed and filtered for the purpose of further removing their solids and liquids. In order to accelerate and increase the reduction of the fumes the pump 21 also delivers at nozzle 25 a continuous spray of solution, which gradually trickles through the granular material with which the trays 23 are charged. The fumes are also acted on by the fluid discharged from the nozzle 25. The suction fan 26 is

mounted in a housing 27 the upper portion of which is connected by the flue 28, to the top of the compartment in which the chambers 24 and 16 are formed.

Having thus described our invention, what we claim and desire to secure by Letters Patent is—

1. In a condensing apparatus, the combination of a liquid containing housing, a drum having a tubular horizontal discharge portion and a receiving head formed of parallel sides of greater diameter than the drum, a spiral wall between said sides terminating at its outer end in a mouth arranged parallel to the axis of the cylinder, said mouth adapted to receive a charge of gas and revolve into the liquid whereby the gas is compressed and discharged from the head into the cylinder, a fixed discharge elbow opening downwardly into the liquid, and a shaft upon which the drum is mounted, said housing and elbow supporting said shaft.

2. In a condensing apparatus, the combination with a liquid containing housing of a rotary drum having a spiral conduit with a receiving mouth at its most distant radial point and a tubular passageway of reduced diameter extending axially from the spiral conduit, and a stationary discharge elbow supporting the tubular portion of the drum by which the liquid in the conduit is discharged into the liquid in said housing.

In testimony whereof we have hereunto set our hands in the presence of two subscribing witnesses.

ANDREW J. HOPPER,
HENRY F. PRINDLE.
